UNITED STATES PATENT OFFICE.

DAVID D. BUICK, OF DETROIT, MICHIGAN.

DESIGN FOR A BATH-TUB.

SPECIFICATION forming part of Design No. 27,669, dated September 21, 1897.

Application filed August 11, 1897. Serial No. 647,926. Term of patent 14 years.

To all whom it may concern:

Be it known that I, DAVID D. BUICK, a citizen of the United States, residing at Detroit, in the county of Wayne and State of Michigan, have invented and produced a new and original Design for a Bath-Tub, of which the following is a specification, reference being had therein to the accompanying drawings.

Figure 1 is a plan view of my tub. Fig. 2 is a side elevation thereof. Fig. 3 is a vertical section on line $x-x$, Fig. 1.

A is the main body of the tub, of the usual oblong trough shape, having at one end the inclined wall B and at the other end the substantially vertical wall C, this latter end preferably rising above the height of the main portion of the tub. D is the bowl, swelling out from the upper portion of this vertical end wall C and at one side of the tub, the greater portion of this bowl overhanging the tub and tapered down to a point E in the vertical center line of the end wall.

F is a rib extending down the wall C from the point E of the bowl.

G is a rim surrounding the upper edge of the tub, which merges into the ring H, sur-

rounding the bowl D, the portions I and J of the rim G being inclined.

The corner formed by the junction of the rim G and the inner side of the ring H is filled out, either by curved section K or so as to complete the rectangle, as shown in dotted lines at L. Either of these shapes may be used without changing the essential character of my design, the leading features of which are, first, the ring H at one end and one side of the rim G, which merges therein; second, the bowl D, swelling out from the end wall of the tub and in greater part overhanging the tub, and, third, the bowl at one end and on one side of the tub, tapering down to a point in the vertical center line of the end wall of the tub.

What I claim as my invention is—

The design for a bath-tub herein shown and described.

In testimony whereof I affix my signature in presence of two witnesses.

DAVID D. BUICK.
